UNITED STATES PATENT OFFICE.

PIERCE D. SCHENCK, OF DAYTON, OHIO, ASSIGNOR TO THE DAYTON MALLEABLE IRON COMPANY, OF DAYTON, OHIO, A CORPORATION OF OHIO.

COLUMN-FORM.

1,175,381.

Specification of Letters Patent. Patented Mar. 14, 1916.

Application filed June 22, 1912. Serial No. 705,217.

To all whom it may concern:

Be it known that I, PIERCE D. SCHENCK, a citizen of the United States, residing at Dayton, in the county of Montgomery and 5 State of Ohio, have invented certain new and useful Improvements in Column-Forms, of which the following is a specification.

This invention has reference to forms for concrete work and the like and particularly 10 to column and capital forms. It has among its primary objects; the provision of an improved form of the character described which is composed of standard sections but which may be readily varied in dimensions; 15 the provision of an improved form comprised of sections adapted to interlock in such manner as to secure great rigidity of the assembled structure; the provision in a sectional form of improved means for drawing the sections rigidly together in assemblage; and in general the provision of a simple and inexpensive form which can be 20 readily assembled and as readily taken apart and adjusted as to size. These together 25 with such other objects as may hereinafter appear or are incidental to the invention I attain by means of a construction which I have illustrated in the accompanying drawings wherein:—

30 Figure 1 is a face view of one of the form sections; Fig. 2 is an end elevation of Figure 1; Fig. 3 is a plan view of an assembled form; Fig. 4 is a side elevation of the joining or filler members connecting the sections; Fig. 5 is an end elevation of Figure 4; Fig. 6 is a section on the line VI—VI of Fig. 4; Fig. 7 is a view showing the arrangement of interlocking means and fastening wedges; and Figs. 8 and 9 are respectively 40 a plan and side elevation of the fastening wedges. Fig. 10 is a section on the line X—X of Fig. 4.

My invention is designed chiefly for columns formed of concrete, cement or other 45 plastic materials adapted to harden or set, and it is particularly designed for the formation of capitals of irregular and ornamental character, its chief purpose being to provide a sectional device of simple construction which can be readily assembled, taken apart and adjusted to various sizes and which at the same time has substantially the rigidity and strength of a one-piece structure.

55 Referring to the drawings, it will be seen

that I have illustrated an octagon capital comprised of eight sections, 3, which are preferably duplicates of one another. These sections may be made of sheet metal but are preferably cast metal and have their sides arranged at an angle to each other, the apex of the angle forming a corner of the capital. On reference to Fig. 1, which is a face view of the upper left hand section of Fig. 3, it will be seen that each section is provided with a flange 4 at the top and with a bent-over flange or ledge portion 5 which constitutes an enlarged base adapted to form a base to the capital or to make joint with either the form for the column or the column 60 itself, as may be desired. Arranged adjacent each vertical edge of a section are sets of lugs, there being four in each set. The upper lugs, 6—6, and the lower lugs, 7—7, are disposed longitudinally of the sections and are provided with substantially 65 vertically disposed apertures 8, while the intermediate lugs, 9—9, and 10—10, are arranged vertically and have substantially horizontally disposed apertures 8'. The outer walls of the various apertures are sloping to fit the wedges 11 and draw the sections securely in position as will herein- 70 after appear. The upper portions of the sections are flared out and are of irregular 75 configuration to add ornamentation to the capital. A plurality of webs are arranged at various points on the outside surface of the sections to prevent warping or other distortion and to lend strength to the de- 80 vice. 85

The means for securing adjacent sections together will now be described, reference being had particularly to Figs. 3 to 7 inclusive. Arranged between the sections are 90 eight joining or filler members 13 which have the same general outline as the sections,—sweeping outward from the bottom portion and having an upper flange portion 4' and a lower base portion 5'. The 95 body of the filler member is substantially a flat plate provided with apertured ears or lugs 15, there being four ears on each side of the filler positioned to receive the sets of lugs of the adjacent sections. The apertures 16 of the upper and lower sets of ears are disposed substantially horizontal and the intermediate sets substantially vertical. It will be noted that the upper three sets of ears or lugs are adjacent curves or bends 100 105 110

in the fillers and are of considerable depth in order to provide a plane surface for the wedges 11 to bear against. This peculiar formation also adds stiffness to the filler members. The edge portions 13'-13' of the filler members are depressed below the central portion and the edges of the sections when the form is assembled lie on the depressed edges 13' and about the central portion in order that the inner surfaces of the assembled form will be flush (see dotted lines Figs. 6 and 10). On the outside face of each of the ears 15 are lugs or abutments 17. The abutments on the upper and lower sets of ears slope toward the body of the filler slightly from the vertical, and the abutments on the intermediate ears slightly from the horizontal.

From inspection of Fig. 7, the manner in which the sections and fillers lock will be readily seen. As there shown, the lugs on the sections project through the apertured ears on the filler members and the wedges 11 are driven in place in the recesses in the lugs. The wedges bear against the abutments 17, the upper and lower wedges drawing the sections and filler members together on a horizontal line, and the intermediate wedges drawing them together on a vertical line.

It will be seen that by this arrangement the sections will be joined together with great rigidity and that any sagging of the overhanging portions will be prevented by the intermediate wedges, and all inner surfaces kept flush with one another. The size of the form can be readily varied by employing filler members of greater or less width than the ones shown without necessitating any change in the other parts. It will be apparent that the sections can be readily assembled and taken apart and that when assembled and locked, are united into a rigid structure.

Copies of this patent may be obtained for five cents each, by addressing the "Commissioner of Patents,
Washington, D. C."

Having thus described my invention and 45 illustrated its use, what I claim as new and desire to secure by Letters Patent is the following:

1. A column form comprising in combination a plurality of sections formed in such 50 manner that the area of the form is greater at the top than at the bottom when the sections are assembled, said sections being provided with a lug adjacent to each end having a substantially vertically disposed 55 aperture and being provided with an intermediate lug having a substantially horizontally disposed aperture, filler members having apertures to receive the said lugs, and having a vertically disposed abutment adjacent to each end aperture and a horizontally disposed abutment adjacent to each intermediate aperture, and wedges for the lugs engaging said abutments and adapted to draw the vertical 60 edges of the sections and filler together and to draw the faces of the sections and filler members flush intermediate the ends thereof.

2. A column form comprising a plurality of sections some of which are provided with 70 openings, apertured lugs on the other sections adapted to fit into said openings, abutments formed adjacent to said openings some of which are disposed substantially 75 vertically and others substantially horizontally, and wedges for the lugs engaging said abutments whereby the vertical edges of the sections are drawn together and the faces of the sections drawn flush when the wedges are driven in place. 80

In testimony whereof I have hereunto signed my name in the presence of the two subscribed witnesses.

PIERCE D. SCHENCK.
